UNITED STATES PATENT OFFICE

OTTO V. HUFFMAN, OF BEDFORD HILLS, NEW YORK

AMMUNITION

Application filed March 26, 1931. Serial No. 525,420.

This invention relates to improvements in ammunition, and is more particularly directed to the provision of an ammunition which is capable when fired from any gun or small arm of being directed a predetermined amount from the normal line of flight at the will of the operator without altering the position of the firing device.

It is an object of this invention to provide an ammunition which when fired from any gun or firearm will deviate from the normal line of flight, and it is a further object and advantage of this invention to provide means for predetermining the amount of deviation from the normal line of flight of a missile fired from any gun or firearm, and furthermore it is within the province of this same invention to embody means for controlling the direction of the line of flight.

A still further object and advantage of this invention lies in the fact that the present-day ordnance consisting of guns and small arms may be used with such ammunition to obtain its peculiar properties without any change in design. It is at once apparent that the saving effected and the confusion prevented in such an object is of great value.

A feature of this invention is that the peculiar behavior of the ammunition of this invention is due solely to changes made in the ammunition and furthermore these changes require little, if any, more expense than would be required in making the standard ammunitions.

In the following specification, which will elaborate and describe the working out of the above objects and features, we shall use the term "bullet" to mean the pellet or missile, commonly of lead or steel, which is discharged from the muzzle of the gun and strikes the target or object fired at. The term "shell" shall include the brass cup in which the bullet is set, the shell containing the powder charge for projecting the bullet and the primer. It is well known that the primer may be either of the center fire or of the rim fire type. In the ammunitions for large guns, it is common to use a projectile with bag powder, so that no "shell," as such, is

used, but such a missile also lies within the comprehension of this invention.

In the present-day art, it is not uncommon to find bullets which are improperly designed, or in which some mechanical defect is incorporated, becoming what is known as "partially upset" at the instant the bullet clears the muzzle of the discharging piece. The technical term given to such a bullet is that it has "kited" or has become "upset," meaning that its line of flight deviates from the normal line of flight to the extent that the point of the bullet was bent on emergence from the muzzle. It will continue in its divergent path subject to the same forces of exterior ballistics that would be present had it "gone out" normally. So far as we have been able to discover, all ammunition makers have tried and succeeded to the limit of practicability in preventing such upsetting of a bullet as it leaves the muzzle of the gun. There are several reasons for this, the main one being that no one was able to tell just where such a bullet would strike. The consequent danger of such a wild flight is obvious.

This invention diametrically departs from such a course and distinctly sets out to provide an ammunition which, as set out above, will deviate a predetermined amount from the normal line of flight and will at the same time be under the control of the man firing the gun as to the direction of the line of flight. It will be observed at once that the bullet may "go out" anywhere around a 360° circle perpendicular to the barrel of the firearm and such emergence is commonly designated in terms found on a clock dial, so that one speaks of a bullet going out at 12 o'clock, 3 o'clock, 6 o'clock, 9 o'clock and so on, indicating a flight upward, to the right, downward, to the left, and so on.

In accordance with this invention, there were two problems which immediately arose. The first was the determination of the angularity of the path of the ammunition of this invention to the path of a normal line of flight traced, let us say, by a standard bullet unchanged along the lines to be set out in our invention. The second problem dealt with

the control of the line of flight. Since we have determined the angularity of the flight line, we also desire to know which direction the bullet will take; in other words, in what 5 direction the bullet will leave the muzzle or go out. The peculiar property allowing a man firing an ordinary gun to direct bullets at will in several directions, while the fire-arm is kept in the same position, is novel 10 and useful, as will be explained hereinafter.

The ordinary gun cartridge or projectile consists of the bullet, the shell containing the powder, and the primer. In carrying out this invention, the parts retain their functional relationship and in addition the shell 15 is not changed mechanically. The same is not true of the bullet, however, and one way which we have found to upset or cause the bullet to kite as it leaves the muzzle of the 20 gun is to bevel the base, in contradistinction to the point, of the bullet. Relative inclinations of the bevel on the base of the bullet will determine relative angularities of its path of flight to the normal path of flight. In 25 all events, it is preferable to have the complete and entire bevel on that portion of the bullet which is gripped within the shell, it being obvious that, if the bevel extended above the edge of the shell, some powder 30 might escape in the handling of that cartridge. Although projectiles for large guns often have no "shells" as such, it is still part of this invention to bevel the base of such a missile to change its line of flight.

35 It has also been found that the direction of upsetting at the instant the bullet emerges from the muzzle is directly related to the position of the bevel in the barrel, since in all cases, as the bullet leaves the muzzle, its point 40 will tip away from the normal line of flight a certain amount determined by the inclination of the bevel on the base, which can be made any inclination within reasonable limits. Thus it may be seen that we can take 45 the ordinary bullet and by placing a certain beveled face thereon of distinct inclination to the axis of the bullet, we can exactly and precisely determine the deviation of that bullet's path after leaving the gun from what 50 we will call the normal line of flight by experiment or otherwise.

If we knew so much and no more, we would still not know what direction the bullet was going to take, although we did know the 55 deviation its line of flight would have. The solution of this second problem lay in exactly determining the rotary set of the shell, and consequently the bullet, in the breech chamber of the firing gun; so that, if we know 60 that when the shell is set in a certain position the bullet will go out at 12 o'clock, we also know that a similar bullet set 180° from the position of the first in the same breech chamber will go out at 6 o'clock; that is to say, 65 downward. Thus, the operator, by control-

ling the rotary set of a cartridge or piece of ammunition in the firing chamber of the gun or firearms may exactly determine in what direction the bullet will go out, the deviation having previously been predetermined in the manufacture of the bullet. It is true that 70 with differing rifling surfaces of different types of firearms, we will need different indicia to indicate the set to be given the ammunition in order that it may go out where 75 we desire. The principles of this invention, having been explained herein and herein-after, make such a task a simple one for skilled testing men in this art.

80 One theory which we advance as our understanding of the behavior of ammunition, although we do not warrant it to be such, is that as the bullet is pushed along in the rifle or firearm barrel by the propelling axis, and just as the foremost edge of the bevel face on the base of the bullet emerges from the muzzle, the gases adjacent that beveled face suffer a loss in pressure not instantaneously 85 shared by the gases shoving on the remaining portion of the base of the bullet, to cause the point of that bullet to tip toward the plane of the beveled face. The amount of tipping, we think, will be determined by the powder charge which is, for all practical effects, kept constant in ammunition of the same type. 90 Knowing the rifling of the firearm device we are dealing with, we can by simple means so set the bevel face of the bullet in the firing chamber relatively to obtain any desired direction of flight. Indeed, it is immaterial in 95 this invention just how the bullet is caused to deviate, how much it deviates, and how the direction of the line of flight of such deviated bullet is controlled, because we have gone directly in the face of established principles of prior and present practice in this 100 art.

105 In order to enable one to more fully understand the advantages of such an ammunition and its usefulness, we are going to set out 110 some cases in which the use of our ammunition, besides being new, is of great practical value. On the modern battleship, there are quite often found what are known as "turret barbettes" over which the various mounted 115 naval guns fire. It is quite possible and oftentimes probable that the arc of swing of such guns would not be sufficient for immediate needs as in time of battle, in which case a projectile following our invention could be inserted in the breech of the guns and fired, and the extra angularity obtained from the ammunition itself combined with the angular position of the turret guns would be sufficient to obtain its object in directing this fire 120 on what would otherwise have been an un- 125 reachable target. Applied in a slightly different manner, we could use our ammunition in anti-aircraft and aircraft guns which needed more elevation before they could se- 130

riously endanger or hit the object they were aiming at. The invention will be found of use also in such instances as shooting into trenches or out of the same and over or around corners with less exposure of the person firing the gun. It is to be expected that new uses will constantly arise all the time to which this invention can be applied.

The principles of this invention are equally applicable to all sizes and types of ordnance and small arm ammunition, as may be appreciated from the objects and aims which are set out in this preamble. Reference to the drawing will now be made to more fully explain the results and purposes of this invention.

Fig. 1 is a diagram showing the change of trajectory resulting from use of a bullet formed according to the invention.

Figs. 2 and 3 show different views of a bullet shaped in accordance with the invention.

Figs. 4, 5, 6 and 7 illustrate methods of predetermining the direction of divergence of the trajectory.

Figure 1 shows a rifle barrel 10 with its normal line of flight 11, drawn as a straight line for purposes of illustration though actually it is in the form of a modified parabola, traced over to a simple target 12. For the present purposes of illustration, the trajectory of every line of flight is not pictured, although present. With our ammunition inserted in the firing chamber of the rifle 10 in its full line position, we can obtain, let us say, a line of flight 13 diverging considerably from the normal line of flight 11. In fact, we obtain the same effect as if gun 10 was pivoted at the muzzle 14 and swung down to dotted position 15 before firing. It is easy to visualize situations in which the firearms or gun will be unable to be moved in such manner, and it is very largely in such cases that the advantages and results of our invention are so strikingly manifest. In the present instance, shown in Fig. 1, the bullet is going out at what is commonly known as 12 o'clock; that is, directly upwards, with a certain angle of deviation formed between the two lines of flight 11 and 13 predetermined by the bevel inclination on the base of the bullet fired from gun 10.

As was set out above, however, just determining the angle of deviation is not in any sense the solution of the entire problem, and we must also determine the rotary set of the cartridge in the firing chamber of gun 10, taking into account its rifling characteristics, before we can make that bullet trace line of flight 13 at 12 o'clock. In Figs. 2 and 3, we show two right angle elevations of a bullet 16 with its beveled face 17 on the base 18 thereof. The reduced neck 19 is usually gripped by the upper edge of the brass shell in the assembled cartridge. It is the position

of this face 17 which when placed in the firing chamber of the gun usually determines in what direction it will go out, and it is the inclination of this same face 17 to the axis of the bullet which will determine the amount of deviation.

Having previously made the bevel on the base of the bullet, we have determined the magnitude of our divergent line of flight, and we must determine in turn which line of flight our bullet is going to take around the 360° clock dial. If such rotary set of the shell in the breech chamber is not effected, it will be seen that the bullet may take any line of flight considered as an element of the cone generated by line of flight 13 as a generatrix swinging about normal line of flight 11 as an axis so that the bullet would have an infinite number of lines of flight around this developed cone of flight. Trajectory in the generating of this cone has also not been included for purposes of simplicity. The matter of determining the rotary set of the shell in the firing chamber of the cone or small arm presents relatively little difficulty, however, and the various methods which were slightly disclosed in the preamble will now be more fully developed.

In Fig. 4, we see the cross-section of the breech of the rifle barrel 10 with the countersunk portion 20 abutting the flange of shell 21, which in this instance happens to be a center fire cartridge. A slight scratch 22 on portion 20 of the rifle is registered by the man firing the gun with a similar scratch 23 on the base of the shell 21. The divergence of the bullet having previously been determined and the rotary set of the bullet in the firing chamber having been exactly made, the operator is able to tell just where his bullet will strike. In place of the scratches 22 and 23, we may, of course, employ grooves, letters, or figures which will permit the same identification as to the position of the bevel face within the shell. Thus in Fig. 4, with the scratches in such position, the bullet, let us say for purposes of argument, will go out at 12 o'clock. The operator then knows that if scratch 23 is placed approximately 90° to the right of scratch 22, the bullet will go out at 3 o'clock and so on.

A somewhat similar arrangement is presented in Fig. 5, in which a small knob 24 adjacent the flange on the base of the shell 21 fits into a notch or groove 25 in portion 20 of the rifle to obtain the same effect in determining the rotary set of the bullet. There may be, of course, several such grooves around the periphery of chamber 20 to permit such a bullet embodying our invention to be fired where the marksman desires. Fig. 6 shows a square shell inserted into a special square breech chamber with the registering scratch indicia 26, 27 to again determine the

rotary set of the bullet, its divergence having been previously determined. In this illustration, the bullet may take any one of four lines of flight.

5 Lastly, we come to the drawing in Fig. 7 which shows the application of two vernier scales 28 and 29 in the rifle chamber and on the shell respectively, such calibration being provided in this case especially for those
10 operators who can see the effect of their shot and may wish to change the rotary set of the succeeding bullet a slight but exact amount. These bullets when used in machine guns are placed in predetermined position in the gun
15 feeder or belt, so that there will be automatic positioning in the barrel of the gun as the belt or feeder passes through.

Thus this invention has taken any gun or
20 small arm in present-day use and supplied it with an ammunition which will depart from the normal line of flight by a predetermined amount, and which will take any direction in the developed cone of deviated flight at the will of the man firing the gun
25 or small arm. The invention is entitled to a broad construction in that it runs directly counter to established practice and principles, it is new and it is useful and capable of many changes embodying the spirit of the
30 invention which is to be defined solely by the appended claims.

I claim:

1. A projectile comprising a head and a base in fixed relation and a single chamfered face on said base.
2. A projectile comprising a head and a base in fixed relation cut by an oblique plane to produce a single beveled surface, inclined to the axis of the projectile, on said base.
3. In combination a breech chamber, a projectile comprising a head and a base, an asymmetric, chamfered face on said base, and means for determining the position of said projectile in said breech chamber.
4. An integral bullet comprising a base and an asymmetric, chamfered face on said base.
5. In combination, a rifled gun, bullet-positioning means on said gun, an integral bullet having an asymmetric base and complementary positioning means on said bullet whereby the rotary set of the bullet in the gun may be determined with respect to said asymmetric base.
6. In combination, a rifled gun barrel, a bullet therefor having an asymmetric base, means for setting said bullet in the barrel with respect to said base whereby a point which the bullet will strike outside the axis of the gun is determined.
7. In combination, a rifled firing piece, a non-jointed projectile therefor having a deformed base, means to determine the rotary set of said projectile in said firing piece

whereby said deformed base will cause said projectile to strike a determined point outside the axis of said firing piece.

8. In combination, a rifled gun, ammunition therefor having a permanent, asymmetric, deformed base and means to determine the rotary set of said ammunition in said gun.

In testimony whereof, I have signed my name to this specification.

OTTO V. HUFFMAN.
